CLAIM

I claim the ornamental design for the interlocking sandal, as shown and described.

DESCRIPTION

FIG. 1 is a top perspective view of the new ornamental interlocking sandal of the present invention.

FIG. 2 is a front view thereof.

FIG. 3 is a top view thereof.

FIG. 4 is a left side view thereof, the right side view being substantially similar.

FIG. 5 is a rear view thereof.

FIG. 6 is a bottom view thereof; and,

FIG. 7 is a top perspective view of the present invention, showing two sandals in an interlocking relationship.

The broken line showing of the sandal upper in FIGS. 1-7 and the second sandal in FIG. 7 is for illustrative purposes only and forms no part of the claimed design.

The top surface is flat.
